UNITED STATES PATENT OFFICE.

STEPHEN W. BOURN, OF PROVIDENCE, RHODE ISLAND.

METHOD OF APPLYING A COATING FLUID.

1,387,963.

Specification of Letters Patent. Patented Aug. 16, 1921.

Application filed September 20, 1920. Serial No. 413,829.

To all whom it may concern:

Be it known that I, STEPHEN W. BOURN, a citizen of the United States, residing at Providence, in the county of Providence and State of Rhode Island, have invented certain new and useful Improvements in Methods of Applying a Coating Fluid, of which the following is a specification.

This invention relates to methods of automatically applying a fluid to the surface of work such as shoes or other articles, and has for its object the provision of means for supporting the work and the fluid-applying device and rotating one relative to the other whereby the fluid such as varnish, shellac, cement or the like, may be applied to predetermined portions of the surface of the work.

The nature and advantages of the invention will be better understood when the following detail description is taken in connection with the accompanying drawings, the invention residing in the combination and arrangement of parts as claimed.

In the drawings forming part of this specification, like numerals of reference indicate similar parts in the several views and wherein:

Figure 1 is a side elevation showing my improved machine on which is shown as being mounted a shoe-upper to which is being applied a layer or narrow line of cement.

Fig. 2 is a plan view of the machine illustrating a shoe-upper and a brush by means of which a narrow line of cement is being applied thereto.

Fig. 3 is an enlarged end view showing the carriage with the shoe form rotatably mounted thereon and in contact with the guide roll.

Fig. 4 is a section on line 4-4 of Fig. 3.

Fig. 5 is a section on line 5-5 of Fig. 3, showing the pins which support the work.

Fig. 6 is a modification illustrating two sets of work-supports connected together to work in unison with each other.

It is found in practice in the construction of shoes, such as tennis shoes and the like, where the foxing portion is secured to the upper by cement, to be of advantage to be able to apply the cement about the lower edge of the upper, automatically, thereby increasing the production, laying the cement more uniformly, and doing away with skilled labor for this service; and the fol-

lowing is a detailed description of one means by which this result may be accomplished.

With reference to the drawings, 10 designates the base of the machine on which is mounted two frame-standards 11 and 12. On the standard 12 I have mounted a plate 13 having its front face provided with two parallel, longitudinally-disposed grooves 14 and in each of which grooves are mounted two rolls 15 to carry the carriage 16, which carriage is supported in position against the face of the plate 13 by means of the bolts 17 passing through the back-plate 18. Positioned against the front face of the carriage-plate I have mounted a form-plate 19 which plate is mounted on and keyed to the rotatable short shaft 20. This shaft is also mounted to rotate in the carriage-plate 16 and in order to permit of longitudinal movement of the carriage this shaft is provided with a roll 21 which rotates with the shaft in the slot 22 formed in the plate 13 while a slot 23 of the diameter of this shaft is formed in the frame-member 12.

A rotating motion is transmitted to this short shaft from the pulley 24 through the pinion 25, gear 26 and telescoping connecting shaft 27, the length of which shaft changes to accommodate the travel of the carriage.

In order to control the longitudinal movement of the carriage 16 on its ways I have provided a guide roll 28 against which the edge of the form 19 rests being held in contact therewith by means of a counterweight 29 through the cord 30 which leads over the pulley 31, but a spring or other suitable means may be employed for this purpose.

The form 19 is always of a shape to control the movement of the work relative to the fluid-applying device, presently described. The work in this particular case is shown to be a shoe-upper to which I desire to apply a narrow line or strip of liquid cement for the purpose of fastening the foxing portion of the shoe sole thereto and in obtaining this particular result I mount a pair of pins 32 on the form 19, which pins are adapted to enter corresponding holes 33 in the last or shoe-support 34, see Fig. 5, and on this last I have mounted a shoe-upper 36 to which the cement is to be applied.

I do not wish to be restricted to the use of any particular device for applying this ce-

ment to a shoe-upper as any suitable means may be employed but for convenience I have herein shown a brush 37 which is mounted on a support 38 extending outward from the 5 guide roll 28, the bristles of the brush being on substantially the same plane as the contact surface of the guide roll whereby by the rotation of the form 19 the surface to be treated is continuously presented to the 10 brush.

The cement may be automatically supplied to the brush from the tank 39 above or other suitable source, through the pipe 40, and by means of this brush a line or narrow 15 strip of cement may be applied about the lower edge of the upper and after one or more coats have thus been so applied the shoe-upper may be removed and the foxing portion applied to this cemented surface, 20 thus saving much time and the employment of skilled labor in performing this work.

Neither do I wish to be restricted to the use of a brush for applying this cement to the work as in some cases a pipe 41 may be 25 employed which is led over the portion to be treated and the fluid may be sprayed or otherwise spread upon its surface.

I have shown and described my improved machine as manipulating a shoe-upper for 30 the purpose of applying cement thereto, but I do not wish to be restricted to the application of cement to a shoe as any other fluid such as varnish or shellac may be applied to any portion of the surface thereof; neither 35 do I wish to be restricted to operating upon a shoe upper in this machine, as the same may be adapted for manipulating and treating the surface of any other kind of work. Then again I have shown the work as being 40 rotated and the fluid-applying device as held in a relatively-fixed position, but in some instances the work may be fixed and the fluid-applying device revolved about the work.

45 I have also shown and described a machine for operating upon a single piece of work, but in some cases a plurality of forms and work-supports may be employed and driven in unison, one arrangement of which con-

struction is illustrated in Fig. 6, both of the 50 forms shown being operated in unison through a sprocket chain 42 working over the sprockets 43.

This fluid-applying machine is very simple in construction and by its use skilled 55 labor may be dispensed with and much time saved in the application of fluids to the surfaces of work to be treated.

The foregoing description is directed solely toward the construction illustrated, 60 but I desire it to be understood that I reserve the privilege of resorting to all the mechanical changes to which the device is susceptible, the invention being defined and limited only by the terms of the appended 65 claims.

I claim:

1. An improved method of spreading a fluid coating upon the surface of work, 70 which consists in providing a non-rotatable spreader and automatically feeding the fluid to the point of application and causing a relative movement between said spreader and the work.

2. An improved method of applying a 75 fluid coating to the surface of work, which consists in rotating the work and automatically feeding the coating material to the applying device.

3. An improved method of applying a 80 fluid coating to work having an irregular surface, which consists in providing a fluid-applying device, rotating and guiding the work to continuously present the surface to be treated to the point of application and 85 automatically feeding the coating material to the applying device.

4. An improved method of applying a fluid coating to work having an irregular 90 surface, which consists in definitely locating a fluid applying brush at a relatively fixed point, rotating and guiding this portion of the surface of the work to be treated, presenting this portion continuously to the brush, and automatically supplying the 95 brush with the coating material.

In testimony whereof I affix my signature.

STEPHEN W. BOURN.
